CLAIM

The ornamental design for a camera connector for medical use, as shown and described.

DESCRIPTION

FIG. 1 is a perspective view of a camera connector for medical use, showing my new design;

FIG. 2 is a front view thereof;

FIG. 3 is a rear view thereof;

FIG. 4 is a top view thereof;

FIG. 5 is a bottom view thereof;

FIG. 6 is a left side view hereof;

FIG. 7 is a right side view thereof; and,

FIG. 8 is an end view thereof, taken along line 8-8 in FIG. 2.

The broken lines showing portions of the camera connector for medical use are for illustrating environmental structure, and form no part of the claimed design.
